UNITED STATES PATENT OFFICE

NORMAN J. ALLBRIGHT, OF CHICAGO, ILLINOIS, ASSIGNOR TO THE ALLBRIGHT-NELL COMPANY, A CORPORATION OF ILLINOIS

HYDRAULIC CURB PRESS

Application filed January 29, 1929. Serial No. 335,945.

This invention relates to a hydraulic curb press.

More specifically, the invention relates to a press of the curb type, in which liquid bearing materials, such as for example cracklings, oil bearing seeds, fruits and the like are fed into a curb in superposed layers separated by metallic plates or similar means and subjected to pressure by means of a vertically acting piston or ram, under the influence of hydraulic or other pressures, in order to force the oil or grease out of the materials. In such presses the liquids oils or greases are collected in a suitable receptacle.

In presses of the character just stated, the material after being deprived of its oil or grease, is in the form of cakes separated by metallic plates or similar means and it is necessary to remove the cakes from the curb before refilling the curb for a succeeding pressing operation.

Presses for this general purpose have heretofore been proposed and used. Such presses were of two general types so far as the manner in which the cakes were removed from the curb and fresh material subsequently fed thereto, is concerned.

In one type the cakes were removed from the bottom of the curb after which fresh material was fed into the curb from the top thereof and the layers formed from the bottom to the top of the press. In such presses the curbs were substantially moved, and jack, chains and other appliances were needed, and a laborious and time consuming series of operations were required to operate them.

In the second type the cakes are removed from the top of the curb after which the material is fed into the top of the curb for a succeeding press operation.

In the first type of press, not only were a comparatively great number of separate operations necessary in each pressing operation with a loss of considerable time and expense of operation, but in this type of press the material was fed into the top of the curb after the plunger was completely retracted and built up in layers from the bottom thereof. Considerable difficulty in proper distribution of the material resulted because the different

layers were not readily visible nor readily accessible to the operator, particularly the lower layers.

In the second type of press, while eliminating many of the operations present in the first type the constructions heretofore proposed were more or less complicated involving in some instances special curb raising means, and did not permit the expeditious carrying out of the pressing operations due to the complexity of the constructions used.

It is a primary object of the present invention to provide a press particularly for the above stated purpose in which the noted objections are obviated.

It is a further object of the present invention to provide a hydraulic curb press of such construction that the oil or grease may be pressed from the material, cakes removed, and in which fresh material may be supplied for a subsequent pressing operation continuously without interruption for the application of appliances and adjuncts between the pressing and cake removing steps.

It is a still further object of the invention to provide a hydraulic curb press in which the material receiving curb is substantially stationary during the operation of the press though mounted so that it may be slightly automatically raised and lowered prior to the ejecting operation and in order to facilitate removal of the top platen respectively as a part of the upward and downward strokes of the power actuated pressing means independently of any other means.

It is a still further object of the present invention to provide a hydraulic curb press of comparatively simple and inexpensive construction adapted for substantially continuous and expeditious use with comparatively little labor and expense.

It is a still further object of the present invention to provide means for association with the curb of a press adapted to cause substantially uniform extraction of liquids from the material being pressed throughout the mass thereof.

Other objects of the invention and the means by which the above enumerated objects are accomplished and the benefits derived

therefrom will be referred to in the course of the following description and as defined in the claims.

Reference will now be had to the accompanying drawing disclosing a preferred embodiment of my invention, and in which Figure 1 is a front elevational view partly broken away and in vertical section of the improved press construction.

10 Figure 2 is a side elevational view, as seen in the direction of arrow 2.

Figure 3 is an enlarged fragmentary sectional view disclosing a packing structure embodied in the invention.

15 Figure 4 is a perspective view of one of the press plate units embodied in my invention, the parts thereof being shown in separated position.

Referring to the drawing by reference 20 characters, in which like characters designate like parts, 10 designates a casting embodying a hollow base supporting member 11 and an inwardly extending cylinder 12 preferably integral therewith. The base supporting 25 member 11 may be provided with integral brackets 13 adapted to engage a floor as indicated by the line 14 and be secured thereto by suitable securing means with cylinder 12 projecting through the floor into a room 30 thereunder. The base supporting member 11 is provided adjacent the corners thereof with apertured bosses 15 for the reception of the inner ends of vertically disposed guide rods 16 which are retained against inner 35 movement within bosses 15 by means of split collars 17, the half sections of which are held in frictional engagement with the rods by bolts 18. The rods are preferably retained against endwise movement in the opposite 40 direction within bosses 15 by nuts 19 threadedly engaged with the inner ends of the rods in engagement with the inner ends of bosses 15.

45 Adjustably and removably supported on the other ends of rods 16 is a head 21 provided with apertured bosses 22 for the reception of said ends of rods 16.

Head 21 is retained against movement in one direction on rods 16 by split collars 23, 50 similar to collars 17, the half sections of which are held in frictional engagement with rods 16 by bolts 24. Said head 21 is retained against movement in the other direction on rods 16 preferably by nuts 25 threadedly engaged with the adjacent ends of the rods 55 and arranged to engage bosses 22. Nuts 19 and 25 are as indicated provided with apertures 26 for reception of a suitable tool for turning thereof.

60 Resting on member 11 and secured thereto, as by bolts 27 are bottom platen supporting members 28 to which are secured, as by bolts 29, the base of a bottom platen 31.

Platen 31 is a hollow casting member provided with a horizontal wall 32 in vertical

spaced relation with the base and defining with the outer wall 33 and an inner conical flange 34 a grease or oil collecting receptacle which is in communication with a suitable outlet 35.

70 Normally resting upon the wall 32 is the base of a curb 36, which, as shown, comprises vertically disposed slightly spaced slats 37 maintained in cylindrical form by comparatively heavy hoops 38.

75 As indicated, the flange engaging base portion of curb 36 is defined by spaced slat extensions defining openings 39 for a purpose later described as well as providing for a more stable seating of curb 36 on wall 32.

80 Adjustably engaged with each rod 16 is a curb stop 41 each comprising a flanged rod engaging section 42 having a hoop engaging extension 43 and a flanged rod engaging section 44, the two sections being drawn into tight frictional engagement with the respective rod 16 by bolts 45 extending through the flanges of the two sections.

85 Disposed between the bottom of head 21 and the top of curb 36 is a top platen 46 which, as indicated, is of substantially cylindrical body formation provided with an upper flange 47 and a lower flange 48, adapted in pressing operations to close the adjacent 90 end of curb 36. The cylindrical body and flanges 47 and 48 of platen 46 merge into a laterally extending web 49 provided with vertically spaced horizontal arms 51 each provided with a flanged rod engaging section 52 to which is detachably connected by bolts 53 a second flanged rod engaging section 54, the sections 52 and 54 being maintained out of frictional engagement with the respective rod 16 in any way, as by suitable shims interposed between the sections, so as to permit platen 46 to be swung outward from curb 36, the sections 52 and 54 providing hinges for the platen. The lower sections 52 and 54 may 95 rest on the adjacent stop 41 to prevent platen 46 moving downward out of operative relation with the top or mouth of curb 36.

100 A suitable platen stop 47' is carried by head 21 for engaging platen 46 to properly locate platen 46 when swung into operative position over curb 36. A suitable handle 46' is carried by platen 46 affording a ready means for grasping the platen for swinging movement thereof.

105 Reciprocably mounted within cylinder 12 is a piston member 55 of cylindrical formation having an inner closed end and an outer open end in which is inserted a tubular extension 56 of a piston head 57, the extension 56 being secured to the member 55 by a brass pin 58.

110 The base supporting member 11 is provided with a central opening 59 concentric with the inner wall of cylinder 12 but of less diameter and a packing ring 61 having an opening 62 coinciding with opening 59 is se- 115

cured to member 11, as by bolts 63. As indicated more clearly in Figure 3 member 11 is provided with a recess 64 opening to the outer surface and opening 59 thereon and packing 5 ring 61 is provided with a locating flange 65 seating within recess 64 in spaced relation to the bottom thereof.

10 A leather packing 66 of U-shape in cross section is disposed in recess 64 and confined therein by flange 65, the packing providing a fluid tight chamber within cylinder 12.

15 As shown in Figure 1 piston member 55 extends through openings 59 and 62 of member 11 and flange 61 respectively and through a central opening 67 in platen 31 with head 57 normally resting adjacent the lower end of curb 36 and piston member 55 is in closely spaced relation to the inner wall of cylinder 12 as indicated in Figure 1.

20 Piston head 57 is provided with a channel 68 V-shaped in cross section on the inner face thereof and adjacent the margin thereof for the purpose later described. The lower end of cylinder 12 is provided with a suitable hydraulic pipe connection 69, whereby fluid under pressure may be admitted to chamber 12 to actuate the press.

25 A plurality of press plate units are provided for positioning in curb 36 between successive layers of material to facilitate the extraction of grease or oil therefrom, one of which units is illustrated in detail in Fig. 4 and a plurality of which are partially shown in Fig. 1 in operative position.

30 Each of the units comprises an imperforate disk plate 71 of a diameter slightly less than that of the interior of curb 36 and preferably approximately $\frac{3}{8}$ inch thick, the plates 71 adapted to be positioned in contact with the upper surfaces of the successive layers of material as indicated in Fig. 1.

35 Each unit further comprises a disk plate 72 of the same diameter as plate 71 but only approximately $\frac{1}{16}$ inch thick to the bottom of which is spot-welded a plurality of ribs or bars 73 in parallel disposition and approximately $\frac{1}{4}$ inch apart, the bars being adapted in operation to engage the outer surface of plate 71 as indicated in Fig. 1 thus defining a plurality of drain channels 74 between plates 71 and 72.

40 Plate 72 is provided with a plurality of relatively small perforations 75 positioned between ribs 73 and a disk shaped #4 duck cloth 76 which may be fixed to the perforated plate is positioned in contact with the upper surface of plate 72, cloths 76 in operative position engaging the lower surfaces of successive layers of material as indicated in Fig. 1.

45 In operation, curb 36 is filled with material from which liquid, oil or grease is to be pressed, the material being arranged in successive layers separated by the press plate units above described, successive layers of material being preferably about 3 inches thick

and each layer being supported on a press plate unit thus providing adequate drainage of liquids from within the layer through the cloth 76, perforations 75 and channels 74. It will be noted upon reference to Fig. 1 that head 57 replaces imperforate plate 71 for the first layer of material.

50 The piston member 55 may be caused to move comparatively slowly in one direction under the action of hydraulic pressure within cylinder 12, and slowly in the reverse direction when the pressure is released.

55 The filling of curb 36 is accomplished during the reverse or downward movement of the piston member as more fully hereinafter described.

60 With curb 36 filled with material and the parts in the position indicated in Figure 1 piston member 55 moves upward pushing piston head 57 upwardly within curb 36 moving curb 36 into tight engagement with flange 48 and then pressing the layers of material between head 57 and the lower surface of said flange.

65 Upon upward movement of piston head 57 within curb 36, the press plate units function as slowly moving pistons as the successive units approach each other as head 57 approaches flange 48 thus effectively subjecting the entire mass of material to a substantially uniform pressure and due to the perforations in plates 72 and channels 74 between plates 71 and 72 the liquid is expressed as effectively

70 from the centers of the layers as from the margins thereof and the oil or grease passes through channels 74 outward through the slits between slots 37 and over the bevelled outer surfaces of hooks 38 into the receptacle in lower platen 31. When the material has

75 been subjected to sufficient pressure to extract substantially all the grease or oil therefrom, which occurs before piston head 57 has reached its upper limit of travel, the pressure on piston 55 is momentarily relieved and platen 46 is grasped by handle 46' and swung

80 outwardly opening the upper end of curb 36. Pressure is then again admitted to chamber 12 and upward movement of piston head 57 continues, moving curb 36 upwardly until upper hoop 38 engages extensions 43, said

85 extensions serving to hold the curb from movement, so that further movement of plunger 57 causes the cakes of pressed material to be ejected from the upper end of curb 36. During this operation the cakes are

90 disposed of and the separating metal plate units collected for the succeeding curb filling operation.

95 When the press cakes have all been forced from the top of curb 36 upon continued upward movement of piston head 57, the hydraulic pressure is released and the piston begins its downward stroke. Coincident with the release of pressure curb 36 moves slightly downward into engagement with

wall 32. During the slow downward movement of plunger 57, a fresh supply of material is fed into curb 36 in successive layers separated by the press plate units, at such rate that when the piston reaches its lower limit the curb is completely filled with a fresh charge of material, whereupon platen 46 is again swung into position over curb 36 above the open outer end thereof for a succeeding 10 pressing operation upon the next upward movement of piston head 57.

It will be noted that curb stops 41 are positioned at a distance above upper hoop 38 somewhat greater than the distance between the 15 top of curb 36 and the bottom of platen 46 in the seated position of curb 36 in order that the open top or mouth of curb 36 may be first pushed into tight engagement with the bottom of platen 46 by the action of the upward- 20 ly moving piston. It will be observed further that the distance between upper hoop 38 and extensions 43 may be such that the curb will be further raised a comparatively short 25 distance after removal of platen 46 at the beginning of the cake discharging stage, so that the inertia of the curb and its contents may be overcome by the plunger before the layers are ejected from the curb.

During the pressing operations upon upward movement of piston head 57 some of the 30 oil or grease will pass between the inner wall of curb 36 and the outer edge of piston head 57 which oil or grease will pass out of the bottom of curb 36, being aided by openings 35 39 and conical collecting flange 34. Some of the oil or grease will collect on piston head 57 and flow over the sides thereof. Channel 68 will prevent capillary action from carrying the extracted material along the under 40 surface of the plunger head so that it will be certain to drip onto flange 34 and thus be prevented from moving inwardly of flange 34 and be discharged over relatively inaccessible portions of the press, and flow over base 11 on 45 the floor.

From the above it will readily be seen that the successive pressing operations are continuously carried out without any interruptions in order to bring auxiliary apparatus 50 such as chains, jacks, etc., heretofore used, into play. At the same time the press may be conveniently filled while the plunger is slowly receding.

The upper platen 46 is mounted for free 55 swinging movement and can accordingly be quickly and easily swung outwardly for ejection of the press cakes and can as easily and quickly be swung back into curb mouth closing position which position is accurately determined by stop 47.

It is to be particularly observed that the removable upper platen not only facilitates the removal of the press cakes upon upward movement of piston head 57 but the construction 60 permits the formation of the succeeding

layers of fresh material closely adjacent the upper open end or mouth of curb 36 where the layers are always visible to the attendant thus enabling him to more uniformly and expeditiously distribute and level the material in the successive layers of the charge of material. 70

It will also be noted that the split collars 17 and 23 are adjustably mounted on rods 16 whereby different sized curbs can be introduced between the upper and lower platens. 75 It will be further noted that all the parts entering into the press construction are removably secured in position as a result of which the press can be quickly assembled or disassembled. At the same time the parts are 80 of relatively simple construction and so arranged that the press can be quickly and easily cleaned. Moreover the construction is such that it can be manufactured and operated at comparatively small initial cost. 85

Having disclosed a single specific embodiment of my invention it is to be understood that the same is merely illustrative and not restrictive as the scope of my invention is to be determined from the subjoined claims and not from the foregoing specific disclosure. 90

What I claim and desire to secure by U. S. Letters Patent is:

1. A hydraulic curb press comprising a press base, a cylinder formed in said base, a vertically operating plunger in said cylinder, a press head, a plurality of parallel supporting rods traversing alined openings in said base and head and disposed around said cylinder, collars on said rods to position said base and head in spaced relation and to prevent separational movement of said head with respect to said base, an annular gutter supported on said base in surrounding relation to said plunger, a platen having a substantial lateral extension provided with means surrounding one of said rods to pivotally secure said platen thereto, sleeves clamped around said last named rod to position said platen beneath said head with capability of swinging movement free of said head to the substantial extent permitted by said extension, a freely floating curb surrounding said plunger and normally resting on said gutter, and an adjustable stop on each of said rods in the form of a sleeve-like clamp embracing a rod and having a lateral extension arranged when in operative position to engage said curb at spaced intervals around its periphery and limit its movement away from said base, said curb being formed so that the liquids expressed by said press drain into said gutter. 110

2. A hydraulic curb press comprising a press base, a cylinder formed in said base, a vertically operating plunger in said cylinder, a press head, a plurality of parallel supporting rods traversing alined openings in said base and head, and disposed around said cylinder, collars on said rods to position said

base and head in spaced relation and to prevent separational movement of said head with respect to said base, an annular gutter supported on said base in surrounding relation to said plunger, a platen having a substantial lateral extension provided with means surrounding one of said rods to pivotally secure said platen thereto, sleeves clamped around said last named rod to position said platen beneath said head with capability of swinging movement free of said head to the substantial extent permitted by said extension, a freely floating curb surrounding said plunger and normally resting on said gutter, and an adjustable stop on each of said rods in the form of a sleeve-like clamp embracing a rod and having a lateral extension arranged when in operative position to engage said curb at spaced intervals around its periphery and limit its movement away from said base and to center said curb between said rods.

3. A hydraulic curb press comprising a press base, a cylinder formed in said base, a vertically operating plunger in said cylinder, a press head, a plurality of parallel supporting rods traversing aligned openings in said base and head and disposed around said cylinder, collars on said rods to position said base and head in spaced relation and to prevent separational movement of said head with respect to said base, a platen having a substantial lateral extension provided with means surrounding said rod to pivotally secure said platen thereto, sleeves clamped around said last named rod to position said platen with capability of swinging movement free of said head to the substantial extent permitted by said extension, a freely floating curb constructed of spaced slats secured together by hoops and arranged in surrounding relation to said plunger and an adjustable sleeve-like clamp on each rod provided with a lateral extension projecting relatively close to said curb to approximately center it and in position to contact with one of said hoops when the curb is permitted to move away from said base by the shifting of said platen.

50 4. A curb for a hydraulic or similar press, comprising an open-ended body formed of a multiplicity of spaced slats secured in position with respect to each other by a plurality of hoops, certain relatively few of said slats being of greater length than the others to constitute legs which when the curb is supported thereon serve to space the ends of most of said hoops substantially above the supporting surface.

60 In testimony whereof I affix my signature.
NORMAN J. ALLBRIGHT.
